H. W. PERSING, OF CENTRALIA, ILLINOIS.

Letters Patent No. 84,757, dated December 8, 1868.

IMPROVEMENT IN WAGON-BOXES.

The Schedule referred to in these Letters Patent and making part of the same.

To all whom it may concern:

Be it known that I, H. W. PERSING, of Centralia, in the county of Marion, State of Illinois, have invented a new and useful Improvement in Wagon-Boxes; and I do declare that the following is a full, clear, and exact description of the construction and operation of the same, reference being had to the accompanying drawing, and to the letters of reference marked thereon, said drawing making a part of this specification.

In the drawing—

A A represent the side-boards of a wagon-box, and B, the end-gate.

The nature of my invention consists of the device attached to the side-boards and end-gate, viz., the movable staples f f, passing through the side-boards A A, just behind the end-gate B; the eccentrics e e, fastened, by means of the bolts g g, to the staples f f on the outside of the side-boards A A; the plates i i, (only one of which is shown in the drawing,) fastened to the side-boards, between the arms of the staples, for the eccentrics e e to work against; and the rods c c, connected by the swivel d, which rods c c pass through or may be otherwise fastened to the cleats h h.

On the ends of the rods c c are hooks, k k, working in the staples f f.

The points on the eccentrics e e, which rest against the plates i i, are flattened, so that they will the more securely remain in position.

The object of the rods c c may be secured by a continuous rod without the swivel, the said continuous rod being bent in the middle in any desired shape, or it may be straight.

The object of the swivel d is to take up any slack that may at any time be found, and thus cause a constant strain to be kept upon the hooks k k when the end-gate B and the eccentrics e e are in position.

The object of this invention is to secure the end-gate B and the side-boards A A firmly in position, and, at the same time, to allow the end-gate to be readily and easily removed or fixed in place.

This device can be attached to any end-gate of any style of wagon-box.

It is operated as follows:

To remove the end-gate, raise the handles of the eccentrics e e, so that the staples f f may be pushed inward, thus loosening the hooks k k from the staples, when the end-gate can be removed. In replacing the end-gate, the hooks k k must enter the loosened staples f f, when, by turning down the handles of the eccentrics e e, the end-gate becomes firmly fastened in position.

What I claim, is—

The combination and arrangement of the eccentrics e e, the staples f f, and the swivel d attached to the rods c c, substantially in the manner described, and for the purposes set forth.

In testimony whereof, I have hereunto set my hand, this 1st day of June, 1868.

H. W. PERSING.

Witnesses:

E. W. JONES,
HEMAN G. HAND.
